(57) **CLAIM**

I claim the ornamental design for a wax ring tray, as shown and described.

DESCRIPTION

FIG. 1 is a top, right, front perspective view of a first aspect of a wax ring tray;

FIG. 2 is a bottom, left, rear perspective view of the wax ring tray illustrated in FIG. 1;

FIG. 3 is a cross sectional view of the wax ring tray taken along line 3 shown in FIG. 1;

FIG. 4 is a front elevation view of the wax ring tray illustrated in FIG. 1;

FIG. 5 is a rear elevation view of the wax ring tray illustrated in FIG. 1;

FIG. 6 is a left elevation view of the wax ring tray illustrated in FIG. 1;

FIG. 7 is a right elevation view of the wax ring tray illustrated in FIG. 1;

FIG. 8 is a top plan view of the wax ring tray illustrated in FIG. 1; and,

FIG. 9 is a bottom plan view of the wax ring tray illustrated in FIG. 1.

The broken line portion of the figure drawings is included to show unclaimed subject matter only for the purpose of illustrating environment and forms no part of the claimed design.

1 Claim, 7 Drawing Sheets
